UNITED STATES PATENT OFFICE.

HARLO L. ERSKINE, OF WASHINGTON, DISTRICT OF COLUMBIA.

HAND-STAMP.

SPECIFICATION forming part of Letters Patent No. 357,587, dated February 15, 1887.

Application filed August 24, 1885. Serial No. 175,226. (No model.)

To all whom it may concern:

Be it known that I, HARLO L. ERSKINE, of Washington, in the District of Columbia, have invented a new and useful Improvement in 5 Hand-Stamps; and I do hereby declare that the following is a full and exact description of the same, reference being had to the accompanying drawings, and to the letters of reference marked thereon.

10 The object of this improvement is to provide hand-stamps adapted to rapidly and legibly print figures, letters, or words on any part of the page of a blank-book or document, and to attain greater dispatch and perfection 15 in such work, especially when the same figures, letters, or words are to be repeated a great number of times. These results are achieved by the mechanism illustrated in the drawings herewith filed as part hereof, in 20 which the same letters of reference denote the same parts in the different views.

Figure 1 is a top view of a hand-stamp embodying the features of my improvement. Fig. 2 is a side elevation of the same. Fig. 25 3 is a longitudinal sectional representation of one end of the device, more fully illustrating the construction and relation of the parts. Fig. 4 is a similar view of the end opposite to that shown in Fig. 3. Fig. 5 is a representation of one of the parts detached.

A is the stamp stock or handle, having flattened sides A', for a purpose hereinafter set forth. The handle A is provided at one end with a reduced extension, a, which fits snugly 35 within and is thereby affixed to a metal cylinder or type-receiver, B, in which is inserted a cylinder-shaped type, D, provided with a transverse recess, d.

C is a spring or latch riveted to the cylinder B, as shown at c, and provided with a rectangular projection, c', which enters the cylinder B and type D through a corresponding perforation and recess in the parts, as fully shown in Fig. 3, and thus secures the 45 connection of the type with the handle A.

The extension a of the handle A serves not only as the means of connecting the cylinder and stamp-handle, but acts as a base or seat for additionally securing the position of the 50 type D.

E F is a type-receiver of similar construc-

tion to the type-receiver B C, and set into a corresponding recess of the handle A, which is provided with a slot, a', for giving access to and clearing the action of the latch F.

The type D may be made either solid or 55 hollow.

Both ends of the handle A may be provided with extensions a, for securing the type-receivers, or both ends may be recessed and the 60 type-receivers inserted therein, as shown at E.

To use the mechanism, the handle is grasped between the fingers at the flat part A', noting the position of the latches, which indicate that of the type, and thus will insure the type being held in a way to leave its impression in proper relative position. The type is supplied with ink by being brought in contact with a pad or other object supplied with ink, when the desired impressions can be made in 70 any desired positions on the document or page of the blank-book much more rapidly than is otherwise practicable. When both letters and figures are necessary to be used in different parts of the sheet or adjacent to 75 each other, the type-receiver E may be provided with either letters or figures, as the case may be; or it may be provided with a pen-point, and the mechanism thus utilized and adapted to saving time by use for manuscript 80 writing.

Having explained the construction and use of my improvement, what I claim as new, and desire to secure by Letters Patent of the United States, is—

The finger-stamp consisting of the handle provided with flattened depressions on two opposite sides for the grasp of the thumb and finger, the sockets at each end of the handle for receiving changeable type, and provided 90 with spring-latches, whereby the types are removably secured in the sockets and the proper position of the character for printing is readily determined, substantially as described.

In testimony whereof I affix my signature in presence of two witnesses.

HARLO L. ERSKINE.
